UNITED STATES PATENT OFFICE.

GEORGE L. COUTER, OF CUMBERLAND, MARYLAND.

SPARK-PLUG.

1,081,660.

Specification of Letters Patent. Patented Dec. 16, 1913.

Application filed July 17, 1912. Serial No. 709,931.

To all whom it may concern:

Be it known that I, GEORGE L. COUTER, citizen of the United States, residing at Cumberland, in the county of Allegany and State of Maryland, have invented certain new and useful Improvements in Spark-Plugs, of which the following is a specification.

This invention relates to spark plugs and has for its primary object the provision of means whereby the terminals may be freed of the carbon deposits which accumulate thereon during the operation of the engine without stopping the engine or removing the plug therefrom.

A secondary object of the invention is to improve, generally, the construction of spark plugs to the end that the efficiency and durability of the same may be increased.

The invention is illustrated in the accompanying drawings and will be hereinafter fully described, the novel features being pointed out more particularly in the claims following the description.

In the drawings: Figure 1 is an elevation of my improved spark plug; Fig. 2 is a central vertical section of the same; Fig. 3 is a bottom plan view thereof; Fig. 4 is a detail section of the lower member of the casing which constitutes one terminal of the plug; Fig. 5 is a detail perspective view of the knife or cleaner.

In carrying out my invention, I employ a bushing 1 which has a reduced threaded tubular extension 2 adapted to be secured in an opening provided therefor in the cylinder of the engine, said reduced threaded extension being cut away at one side, as indicated at 3, and having a lip 4 projecting inwardly opposite said cut-away portion to constitute a terminal. The said bushing 1 forms a grounded connection through the cylinder with the battery or magneto generator, and the lip or terminal 4 co-acts with an inner terminal to form a spark gap. The upper outer portion of the bushing 1 is angular, as shown clearly in Figs. 1 and 3, to facilitate its engagement by a wrench or other tool when it is being fitted in the engine cylinder. The upper portion of the bushing is hollow, as shown in Fig. 4, and an upper metallic body or sleeve 5 is threaded into the upper end of the bushing to constitute a casing or support for the inner members of the plug. The lower extremity of this casing or sleeve 5 is threaded, as

clearly shown in Fig. 2, to engage the upper threaded extremity of the bushing, and between its ends the said sleeve or casing 5 is provided with an annular angular rib or flange 6 to facilitate its engagement in the bushing. Above the said flange 6, the casing or sleeve 5 is externally threaded, as shown in Fig. 2.

A sleeve or tubular plug 7 of porcelain or other insulating material is inserted through the casing 5 and the bushing 1, and the said sleeve or tubular plug extends through and slightly beyond the reduced extension 2 of the bushing, as shown clearly in Fig. 2. Between its ends, this sleeve 7 is provided with an annular rib or flange 8 which lies within the upper hollow or socketed portion of the bushing, and above and below the said rib, I provide asbestos or other packing 9 which fills the space between the said rib and the lower end of the casing 5 and between the said rib and the internal annular shoulder 10 formed in the bushing. When the casing 5 is turned home, the insulating sleeve will be securely clamped between the ends of the same and the shoulder 10 of the bushing, as will be readily understood. The said insulating sleeve is provided with a slight annular shoulder 11 near its lower end and within the said sleeve is inserted the metallic sleeve or tube 12 having an enlarged lower end or head 13 adapted to fit against the annular shoulder 11, whereby, when the nuts 14 and 15, mounted on the threaded upper extremity of the said tube, are turned home against the upper end of the insulating sleeve, the tube will be securely clamped within the insulating sleeve. The head 13 of this metallic tube is constructed with diametrically opposite longitudinal slots or recesses 16, and from its lower end depends a small pin or hook 17 constituting the electrode terminal adapted to co-act with the lip or electrode 4 to form a spark gap. The nuts 14 and 15 not only serve to secure the metallic terminal tube 12 above the insulating sleeve, but also form a clamp to secure the end of the wire or conductor leading to the source of electricity.

Extending through the metallic terminal tube 12 and adapted to reciprocate therein is a rod 18 having its upper threaded extremity 19 projecting above the tube to receive an adjusting nut or collar 20, between which and the end of the tube 12, or the

nuts thereon, a spring 21 is coiled around the threaded extremity of the rod. This spring serves to hold the rod normally raised and a cap 22 of insulating material is fitted over the upper end of the rod, the nut or collar 20 and the end of the spring to form a convenient handle or button by which the rod may be actuated against the tension of the spring when it is desired to clean the electrodes. The lower portion of the rod 18 is enlarged, as shown at 23, and this enlargement fits within an opening or socket provided therefor in the tube 12. Below the enlargement 23 the rod is flattened and projected laterally to form a knife or blade 24 which, in the normal position of the parts, will be accommodated in the slots or recesses 16, as shown in Fig. 2. The several parts are so arranged that the plane of the said scraper or blade 24 lies between the planes of the terminals 4 and 17, so that, if the rod be projected, it will pass between the said terminals, as will be readily understood on reference to Fig. 3.

The rod may be pressed downwardly or inwardly against the tension of the spring 21 by the manual application of force to the cap or button 22, but to more conveniently operate the device, I provide an angle lever 25 which has one arm bearing upon the said cap 22, as clearly shown, and its other arm provided with an opening 26 to permit attachment of a chain or other flexible device 27 which may be carried to any point convenient to the engineer. The angle lever 25 is fulcrumed in the upper end of a standard or post 28 which has its lower end formed into an eye or ring 29 adapted to fit over the casing 5 and rest upon the annular rib 6 thereof and be clamped to said rib by a nut 30 mounted on the threaded upper extremity of the said casing and turned home against the eye or ring, as clearly shown and as will be readily understood.

It is thought the operation and advantages of the device will be readily understood from the foregoing description, taken in connection with the accompanying drawings.

It is well known that in the operation of internal combustion engines the electrodes are coated with soot or other carbon deposits, so that, unless the electrodes are frequently cleaned, the engine will operate in a very unsatisfactory manner or not at all. With my invention, it is not necessary to stop the engine or remove the plug from the engine cylinder in order to free the electrodes of these deposits, as a few strokes of the blade 24 will effectually clean the electrodes and remove the deposits therefrom without requiring any stoppage of the engine. When pressure is applied to the upper end of the rod 18, the spring 21

will be compressed and the blade 24 projected between the electrodes 4 and 17, as will be readily understood on reference to Fig. 3, so that the soot or other foreign matter which has collected upon the electrodes and tends to close the spark gap to prevent the formation of the spark will be effectually broken off, so that the electrodes will be clean and all obstructions to the formation of the spark will be destroyed. When the pressure upon the rod is removed, the spring 21 at once expands and returns the same to its initial position. The slots 16 in the head of the inner terminal tube serve as guides for the blade 24 so that said blade will be maintained in its proper position relative to the electrodes and consequently will be prevented from striking either electrode and consequent damage to the blade or the electrodes is avoided. It will be readily noted that the construction of the several parts of the plug is such that, while the members are securely fastened in their proper relative positions, the plug may be easily and quickly assembled and disassembled so that the expense of manufacturing the same and applying it to the engine will be kept down to an economical basis.

What I claim is:—

1. A spark plug comprising a bushing having an electrode formed on its inner end, a terminal tube disposed within the bushing and having an electrode formed on its lower extremity spaced from the electrode on the bushing, a blade mounted slidably within the terminal tube and adapted to be housed and prevented from rotating by said tube, and means for projecting the said blade between the electrodes. 95

2. A spark plug comprising an outer electrode, an inner terminal tube provided at its lower end with an enlarged slotted head and having an electrode depending from the said head, a blade slidably mounted in said terminal tube and engaging the slots of said head and held against rotation thereby and arranged in a longitudinal plane of the spark plug passing between the opposed adjacent faces of the electrodes, and 100 means for reciprocating the said blade. 105

3. A spark plug comprising an outer electrode, an inner terminal tube having an enlarged head at its lower end provided with longitudinal slots, and an electrode depending from said head a rod slidably fitted in the said terminal tube and carrying at its lower end a blade engaging the said longitudinal slots, and held against rotation thereby means for holding the said rod yieldably retracted within the terminal tube, and means acting on the said rod to project the same whereby the blade will be caused to pass between the electrodes. 115 120 125

4. A spark plug comprising a bushing 130

having an electrode formed on its inner end, an insulating sleeve secured within said bushing, an inner terminal tube secured within the said sleeve and provided with 5 an electrode co-acting with the electrode on the bushing, a rod slidably fitted within the said terminal tube, a blade carried by said rod and guided by said tube to be projected between the electrodes, a spring acting upon the rod to hold the same normally retracted, a post supported above the bushing, and an angle lever fulcrumed in said post and bearing upon the slidable rod to project the blade between the electrodes. 10

15 5. A spark plug comprising a bushing having an electrode at its inner end, an insulating sleeve fitting within the bushing, said sleeve having an internal annular shoulder near its lower end, a casing secured in 20 the upper end of the bushing and adapted to clamp the insulating sleeve therein, a terminal tube inserted through the insulat-

ing sleeve and provided with an internal shoulder, an enlarged head on the lower end of the terminal tube adapted to engage the 25 internal annular shoulder of the insulating sleeve, and provided with longitudinal slots, means on the upper end of the terminal tube to secure the same within the insulating sleeve, a slidable rod mounted within 30 the terminal tube and constructed to engage the internal shoulder of the same, a blade carried by the said rod and having its side edges playing in the slots in the head of the terminal tube, said rod being adapted 35 to be projected to carry the blade between the terminals, and means acting on the said rod to hold the same normally retracted.

In testimony whereof I affix my signature in presence of two witnesses.
